Des. 209,421

Patented Nov. 28, 1967

209,421

GUIDE CHANNEL FOR CONVEYER BELTS

Thomas R. Fabian, Hubbard, Ohio, assignor, by mesne assignments, to Dynamic Systems, Inc., Girard, Ohio, a corporation

Filed Dec. 21, 1966, Ser. No. 5,143

Term of patent 14 years

(Cl. D55—1)

FIGURE 1 is a perspective view of the guide channel for conveyer belts, showing the top and one side thereof.

FIGURE 2 is a perspective view showing the bottom and the other side thereof.

I claim:

The ornamental design for a guide channel for conveyer belts, as shown.
